STOCK BENDING AND SHAPING DEVICE

Frank Suhi, Chicago, Ill.

Application June 4, 1935, Serial No. 24,954

7 Claims. (Cl. 153—33)

This invention relates to an especially designed and constructed device for bending and shaping metal stocks, and has reference in particular to a distinctively constructed means for converting rectilinear rods and cylindrical tubes into 5 curvilinear formation for diversified usage.

In keeping with an urgent desire to provide a simple and economical structure for accomplishing the requisite results with expediency and efficiency I have found it practicable to adopt a duplex unit assembly or structure wherein the units are disposed in superposed converse relationship and provided with properly arranged and coinciding bending and shaping elements whose collective force, when brought together, 10 is reliable in forming compound curves of uniform and corresponding proportions to an extent not heretofore obtained by relatively complicated machinery now available.

I have discovered by providing this double-acting assemblage and constructing the units of substantially identical companion parts it is possible to not only satisfactorily form the desired compound bends, but to regulate the shaping thereof to insure the formation of predetermined 20 uniform undulations.

Aptly fitted for the purposes intended, I have devised a systematic coordination of parts wherein each unit embodies a spring returned adjustably mounted tiltable adapter block for stock holding purposes, together with a shaping mandrel or die, the blocks being disposed at the outer ends of the respective units and the mandrels at the inner ends so that they come together in 30 proper matching relationship to simultaneously 35 coact in satisfactorily keeping the tube in place while bending or shaping it around the forming mandrels.

The preferred embodiment of the invention is 40 illustrated in the accompanying pictorial drawings in which:

Figure 1 is what may be designated as a side elevational view of the double unit assembly with the units occupying their relative operative positions before the bending operation is started.

Figure 2 is a view like Figure 1 showing how the units come together and form the bends or undulations between the parts forcibly pressed or clamped thereagainst.

Figure 3 is a longitudinal sectional view of the lower or relatively stationary unit, taken on line 3—3 of Figure 4.

Figure 4 is a top plan view thereof.

Figure 5 is a vertical or transverse section on 50 the line 5—5 of Figure 4.

By way of introduction to the detailed description, it is to be pointed out that the two complementary units denoted by the numerals 6 and 7 are virtually duplicate in construction and while the same numerals might well be employed to 5 designate the corresponding or identical parts it is believed desirable to represent them by distinguishing reference characters. It follows, therefore, that the relatively fixed unit 6 comprises a base plate 8 attachable to an appropriate 10 collateral foundation (not shown). Rising from one end of the base plate are flanges 9 disposed in spaced parallel order and of appropriate height. These are provided with selectively usable bearing holes 10 to accommodate the pivot 15 pin 11 for the tiltable anvil or block 12 disposed between said flanges. This block is of general rectangular form having the inner end thereof cut off obliquely as at 13 to permit it to swing down toward the plate 8 as illustrated in Figure 20 20. The upper edge is formed with a groove 14 of appropriate depth to accommodate the rectilinear pipe, tube, rod or the like indicated at 15. This block is adjustably mounted between the flanges through the instrumentality of the 25 pivot pin 11 and the bearing holes 10 as is evident. At the opposite end of the plate are similar 30 upstanding flanges 16 of appropriate shape between which is mounted a non-turnable "roller" 17. This is the die or mandrel for bending the pipe. 30 It is provided with a peripheral groove 18 which corresponds to the groove 14. The mandrel is fastened between the flanges by way of an attaching pin 19 secured to said flanges. That 35 part of the roller which contacts the base plate 8 is flattened to retain the roller against rotation.

Referring now to the upper relatively movable unit 7 it will be observed that this comprises a 40 flat plate 19—a of proportions more or less equal to the plate 8, it being disposed in parallelism to said plate 8 and movable toward and from the plate in a direction at right angles. This plate 19—a carries an attaching stub shaft 20 which is connectible with the source of power 45 such as the press or punch machine (not shown). Depending from the right hand end of the plate are spaced parallel flanges 21 having selectively usable bearing openings or apertures 22 to accommodate the pivot and attaching pin 23 of 50 50 the tiltable clamping block 24. This block corresponds in proportion and shape to the first named block 12, having the same features 13 and 14. Both of these blocks are provided with headed pins 25 at the outer end and a coil spring 55

26 is attached to this pin and to a similar headed pin 27 on the base plate. This is a simple spring return means for normally maintaining the block in a plane parallel to the plates and at the same time allowing it to tilt to the requisite angle as shown in Figure 2. The flanges 28 on the inner end of the plate 19a are like the flanges 16 and constructed to accommodate the mandrel or "roller" 29. This is fastened in place by the same sort of a pin 19 and provided with a marginal or peripheral groove 18 to accommodate the pipe. Thus, it will be seen, that the two units 6, and 7 are approximately duplicate in construction and are disposed in superposed parallelism, the unit 7 being offset with respect to the unit 8 so that the parts come together in requisite interfitting relationship as depicted in Figure 2. Or stated otherwise as the unit 7 is forced down under proper force and pressure the two blocks 12 and 24 automatically swing to tilted parallelism, while the two mandrels 17 and 29 move into close coacting proximity in such a way that the pipe 15 clamped between the mandrels and blocks is formed into a compound or reverse bent curve. The coacting of the force of pressure on the pipe is such that the bends are substantially uniform in shape and proportion. When the unit 7 is elevated the blocks 12 and 24 resume their normal horizontal position.

It is believed that a device of this type is characterized by appropriate cooperating improvements so matched and inter-related as to permit the results obtained thereby to transcend in accuracy and dependability though accomplished by far more complicated and expensive machines. It is believed therefore, that the invention fulfills the requirements of a simplified structure of the type claimed and is something which may be endorsed by the trade as an improvement.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details coming within the field of invention claimed may be resorted to in actual practice, if desired.

Having thus described the invention, what is claimed as new is:

1. In a structural assemblage of the class described, in combination, a relatively fixed support, a circular mandrel mounted thereon and provided with a peripheral stock receiving and retention groove, an adjustably and tiltably mounted holding member on said support properly coordinated in relation to said mandrel, a relatively movable unit independent of said first named unit and having a corresponding mandrel movable in a line at right angles to said support to allow it to position itself between the first named mandrel and tiltable member, said relatively movable unit being also provided with a tiltable stock holding member bodily movable to a position outwardly of and in close proximity to said first named mandrel.
2. In a structure of the class described, a support provided at one end with upstanding spaced parallel apertured flanges, a substantially rectangular horizontally disposed block adjustably and pivotally mounted between said flanges, spring mean attached to the swingable end of

the block and adjacent end of the plate for normally maintaining the block in a position parallel above the plate, the inner end of the block being beveled, and means at the opposite end of the plate for shaping and bending a pipe, 5 tube or the like.

3. As a component part of a structural assemblage of the class described, a base plate provided at one end with upstanding spaced parallel apertured flanges, a spring returned rectangular block adjustably and pivotally mounted between said flanges and having its inner end beveled to approach the plate when tilted, and having its upper edge formed with a pipe reception and retention groove, said plate being 15 provided at its opposite end with a non-rotatable peripherally grooved roller.

4. In a stock bending and shaping structure of the class described, a support provided at one end with a pair of upstanding spaced parallel flanges, said flanges being provided with longitudinally spaced bearing holes, a horizontally disposed block mounted between said flanges, said block being provided with a hinge pintle selectively disposable in said bearing holes, spring return means connected with the support and block, and normally maintaining the block in a position parallel to the support, the inner end of said block being bevelled to permit it to swing toward and from the support, an additional pair 30 of flanges on the support adjacent the opposite ends and spaced longitudinally from the first named flanges, and a shaping mandrel mounted transversely on the support between said second named flanges and spaced longitudinally from 35 and disposed in a plane with said block.

5. In a device of the class described, a base provided at one end with a tilttable spring returned horizontally disposed longitudinally elongated block formed in its upper edge portion with a pipe reception and retention groove, one end portion of said block being transversely cut on an oblique line to provide a bevelled surface swingable into close proximity to the base when the body portion is tilted in a direction 45 away from the base, and a relatively fixed shaping mandrel on said base spaced longitudinally from and disposed in a plane with said block.

6. In a stock bending and shaping structure of the class described, in combination, a relatively 50 fixed support, a shaping mandrel mounted rigidly on said support, an adjustably and tiltably mounted stock holding member on the support spaced longitudinally from said mandrel, a complementary relatively movable unit disposed in a 55 plane above said support and movable in a perpendicular line toward and from the support, said unit being provided with a fixed shaping mandrel located in a position to move down between said first named mandrel and stock holding member, and an additional stock holding member carried by said unit and constructed and arranged to move downwardly to a position spaced outwardly of said first named mandrel.

7. A stock bending and shaping apparatus of 65 the class described comprising a relatively fixed unit having self adapting stock holding means and a shaping mandrel, said mandrel being spaced longitudinally from said stock holding means, and a relatively movable unit independent of the first named unit adapted for cooperation with operating means and disposed in spaced parallelism above said first named unit and movable at right-angles toward and from said first named unit in a substantially 70 75

perpendicular line, said movable unit comprising a support provided on its under side at one end with a spring returned tiltably mounted stock engaging a holding block, said block being positioned in a direction outwardly of and beyond said mandrel, and a second mandrel corresponding in construction to the first named

mandrel and spaced longitudinally from and in a plane with said block and adapted to move, when in stock bending position, to a point between the first named mandrel and stock holding means.

FRANK SUHI.
